UNITED STATES PATENT OFFICE.

CHARLES ASHTON HENRY BULLOCK, OF LONDON, ENGLAND.

STAMP-AFFIXING MACHINE.

1,109,105.

Specification of Letters Patent.

Patented Sept. 1, 1914.

Application filed August 12, 1912. Serial No. 714,685.

To all whom it may concern:

Be it known that I, CHARLES ASHTON HENRY BULLOCK, a subject of the King of Great Britain, residing at London, in the county of London, England, have invented certain new and useful Improvements in Stamp-Affixing Machines, of which the following is a specification.

This invention relates to an improved machine for delivering and affixing postage stamps and the like and has reference to machines of the kind wherein the operation of the plunger serves to feed a stamp forward, sever it and apply it to a surface and at the same time operate a counter or recording device.

The object of the present invention is to provide a more simple and reliable machine than those hitherto proposed and the invention comprises various important features of novelty which will hereafter be more particularly described and set forth in the claims.

Among these primary features of the invention may be specifically mentioned the feeding device wherein when the plunger is depressed the stamp strip is automatically gripped and fed forward the required distance, a pin or tooth or a plurality thereof adapted to always spring back to a definite point automatically operating in conjunction with the perforations in the stamp strip to regulate and correct the feed.

Secondly the damping device is important, the essential feature of which damping device is that jets or sprays of moisture are ejected from the machine preferably intermittently in such a manner and in such a direction that the moisture is sprayed on to the adhesive side of the stamp to be affixed as the stamp moves into position for affixing.

Another feature consists of the particular arrangement of the plunger pad which presses the damped stamp on to the surface to which it is to be applied, the arrangement being such that instead of a vertical pressure only being available there is a slight horizontal movement of the pad such as will cause a more firm adherence.

Other features of importance comprise means for rendering a complete stroke of the plunger imperative at each operation and means for insuring the proper application of the stamp to the surface designed to receive it.

The invention moreover comprises the

construction, arrangement and combination of parts hereinafter set forth.

In the accompanying drawings Figure 1 is a sectional elevation of the complete machine. Fig. 2 is a perspective view of the stamp spool carrier and stamp strip guide and its fittings. Fig. 3 is a perspective view illustrating the method of operating the water ejection. Fig. 4 is an underplan view illustrating a form the clearing device may take. Fig. 5 is a sectional view illustrating the device for rendering a complete stroke of the plunger imperative at each operation, and Fig. 6 is an underplan view thereof on line A—A of Fig. 5.

Referring to the drawings, the numeral 1 designates the machine plunger, which slides in an opening 2 in the casing 3 and is adapted to normally adopt its highest position under the influence of springs, such, for instance as the springs 4. Rigidly secured in a suitable manner to the plunger 1 a feeding arm 5 is provided. This feeding arm 5 is spring controlled preferably by the resilience of the arm itself so that its pins or gripping members 6 always tend to remain out of engagement with the stamp strip 7.

The numeral 8 designates the guide down which the stamp strip 7 passes from the roll 10 which is carried upon the spindle 11 and is housed within the circular extension of the machine casing. Normally the pins or gripping members 6 of the feeding arm 5, are, as aforesaid, held away from the stamp strip. When, however, the plunger 1 is depressed the pins or rollers 12 carried by the feeding arm 5 engage the track or way 13 and thus the pins or the like 6 are forced into engagement with the stamp strip 7, 95

grooves 14 in the stamp strip guide accommodating the free ends of the pins. As the stamp strip is gripped the teeth or the like 16 upon the ends of the spring controlled arms 17 which teeth normally engage in the perforations of the stamp strip are lifted out of these perforations by reason of the pins or rollers 12 depressing the blocks 17^a and raising the teeth 16 by means of the wire 17^b. Immediately the pins or rollers 12 leave the blocks 17^a—that is when the stamp strip has been moved forward a short distance—the teeth 16 contact with the stamp strip again in readiness to spring into the next row of perforations and the stamp strip is free to move and as the plunger 1 continues its descent the strip is moved

forward and a stamp is ejected through the slot 19 in the member 20. When however a complete stamp has been extruded through this slot 19 the teeth 16 will enter the next 5 set of perforations in the stamp strip and prevent further movement and the knife 21 carried by the plunger will sever the stamp. The arms 17 are pivoted in saw cuts in the block or carrier 16^a which is pivoted at 16^b to the framework of the machine. Each of 10 the arms 17 is controlled by a spring 16^c. By this means the stamp strip can be fed forward a little too far at each operation, the block or carrier moving about its pivot 15 to permit the slight longitudinal movement of the teeth 16 necessary, the block or carrier 16^a then moving back again about its pivot under the influence of the springs 16^c, a stop 16^d being provided to insure the block or 20 carrier 16^a, and consequently the correcting teeth 16, always adopting the correct final position.

While however the feeding forward of the stamp is taking place the damping of the 25 stamp is effected in the following manner: The plunger 1 carries a rack 22 preferably upon the side of the knife, and as this rack 22 descends with the plunger it engages a pawl 23 carried upon one end 24 of the lever 30 25. The lever 25 is pivoted at 26 and its end 27 depends into the tank 28. The pivot 26 is preferably of some length and well fitted so as to prevent any leakage even if the machine is inverted. The extremity of 35 the depending end 27 of this lever 25 is connected to a sliding plunger carrier 29 and this plunger carrier 29 has at its free end a rubber or other yielding plunger 30, the plunger 30 normally closing the jets or 40 nozzles 31 proceeding from the bottom of the tank. The nozzles 31 are so located and bored in such a direction that the moisture ejected through them is sprayed on to the under adhesive surface of the stamp which is 45 being fed forward through the slot 19. The movement of the rack 22 causes a vibration of the lever 25 and thus the plunger 30 is intermittently oscillated and water flows from time to time to the nozzles or jets 31 as 50 the plunger 30 withdraws and the water in front of this plunger 30 is then ejected through the nozzles or jets 31 as the plunger flies out again.

Immediately prior to the severing of the 55 stamp the pivoted arm 32 is operated in the following manner: The pin or roller 33 carried by the plunger operating in the slot 34 causes the plate 34^a which is pivoted to the machine casing to move and the teeth 34^b 60 at the lower end of this plate 34^a cause a partial rotation of the pinion 35, from which the arm 32 proceeds. Thus the arm passes beneath the stamp and lifts its free edge clear of any obstruction and adopts a 65 position at right angles to its normal posi-

tion. The damped stamp is then cut off by the knife 21 as it passes the slot 19 and simultaneously the stamp will be pressed on to the envelop or other desired surface beneath it. The pad 36 which presses the stamp on 70 to the envelop or the like is as aforesaid of special construction and operates in a particular manner. This pad is pivoted at 37 to the lower end of the plunger 1 and by means of the spring 38 or some other suitable 75 yielding device it normally adopts an angle to the horizontal as shown. The effect of this is that almost simultaneously with the severing of the stamp by the knife the edge of the pad contacts with the side of the 80 stamp remote from the severed edge. The continued descent of the plunger 1 causes the pad to gradually come into the horizontal position and thus the stamp is affixed by a 85 horizontal movement and a vertical pressure, and it will be readily apparent that this is the movement required to cause a firm adhesion of the damped stamp, upon this surface. Moreover, this particular movement of the pressing pad has the advantage 90 that the air between the stamp and the surface to which it is to be applied is expelled gradually as the pad approaches the horizontal and thus there is no danger of an air bubble becoming imprisoned beneath the 95 stamp.

The movement of the plunger operates a counting device 39 in the usual manner and it is so arranged that the counter must be 100 operated immediately the stamp strip commences its delivering movement. In order to render a complete stroke of the machine plunger imperative at each operation the plunger 1 is provided with a rack 40. This plunger slides through an opening 2 in the 105 top of the machine casing. On the under surface of this machine casing a pawl 41 is provided and this pawl is controlled by a spring 42 which engages in a groove 43 in its underside. This spring normally has 110 its free end disengaged from a notch or catch 44 and thus the nose of the pawl is rendered capable of engaging the teeth of the rack when the plunger is depressed. It will be seen however that the teeth of 115 the rack are such that the plunger can be depressed, the teeth of the rack passing over the nose of the pawl 41. If however the stroke of the plunger 1 has been only partially completed, the plunger cannot be returned 120 to the normal position since the nose of the pawl would immediately engage the teeth of the rack. When however the stroke has been completed the nose of the pawl engages the incline 45 at one end of the rack 125 40 and the pawl is pushed back against the influence of its spring 42 and the free end of this spring flies into the notch or catch 44 and thus holds the pawl out of the engaging 130 position and permits the spring controlling

- machine plunger to return to the normal position under the influence of its spring or springs 4. When however the plunger reaches the normal position, the free end of the spring 42 contacts with the pin or projection 46 and is thus automatically disengaged from the notch or catch 44 and the pawl is again rendered ready for engagement with the teeth of the rack.
- 10 In order to prevent the machine being operated accidentally as by a child I provide the locking lever 47 pivoted at 48 and so arranged that if the knob 49 is pushed in the lower end 50 of the lever will engage the top of the machine casing and prevent the depression of the plunger until said knob is pulled out again.
- 15 It will be understood that the details of construction of the machine can be varied in many ways within the scope of my claims.

- 20 What I claim and desire to secure by Letters Patent is:—
1. In a stamp affixing apparatus, a casing, a plunger having one end operating in the casing, a stamp roll supporting device and a stamp moistening means associated with the stamp roll supporting device, a stamp guide for guiding the stamps from the stamp roll to the plunger, a stamp feeding mechanism within the casing, said feeding mechanism comprising pins supported by a depending flexible arm, and means in the cas-

ing for forcing the pins into engagement with the stamps of the stamp roll.

2. In a stamp affixing apparatus, a casing, 35 a plunger operating in the casing, a stamp roll supporting device forming a part of the casing, a stamp guide for guiding stamps to one end of the plunger, a stamp feeding apparatus comprising pins supported by a 40 flexible arm, the said arm being movable with the plunger, a roller on one end of the arm, means adapted to coöperate with the roller for forcing the pins into engagement with the stamps of the stamp roll. 45

3. In a stamp affixing apparatus, a casing, a plunger operating in the casing, a stamp roll supporting device disposed adjacent one side of the casing, means for guiding the stamps from the stamp roll supporting device to the lower end of the plunger, a stamp feeding mechanism comprising pins supported on a flexible arm, said arm adapted to move with the plunger and means on one end of the flexible arm for engaging an inclined track for forcing the pins into engagement with the stamp strip. 50 55

In testimony whereof, I affix my signature in the presence of two witnesses.
